CASH REGISTER

Wilhelm Kropff, Berlin-Charlottenburg, Germany, assignor to The National Cash Register Company, Dayton, Ohio, a corporation of Maryland

Application January 24, 1929, Serial No. 334,792
In Germany April 21, 1928

23 Claims. (Cl. 235—130)

This invention relates to registers and like machines, with particular reference to locking mechanisms for cash registers.

Cash registers and accounting machines generally are provided with manipulative means adapted to be moved into a plurality of positions to control the machine for adding, totalizing, and sub-totalizing operations.

However, to prevent the operators and clerks from acquiring a knowledge of the total amount of business transacted, for example, or other information accumulated in the register which the proprietor wishes to maintain secret, it is often desirable to render certain of the positions into which the manipulative control means may be moved, inaccessible to all but the proprietor or other duly authorized persons. This has been accomplished, heretofore, by providing a plurality of bolts controlled by removable keys, and adapted to prevent the adjustment of the manipulative means to certain of its positions, but this method has been found slow and cumbersome.

It is, therefore, an object of this invention to provide, in a cash register or accounting machine having an adjustable state-controlling device, a novel locking means whereby a single lock operated in conjunction with said adjustable device, determines whether or not the machine shall operate when the state-controlling device is in one or another of its positions.

Another object is to provide a novel controlling mechanism whereby a state-controlling device, adjustable to a plurality of positions, is free to be moved to any of its controlling positions, but which, when moved to certain thereof, prevents the operation of the machine.

Another object is to provide a novel controlling means whereby movement of a state-controlling device to certain of the plurality of positions to which it may be adjusted, prevents operation of the machine, and movement of the state-controlling device to certain other of its adjusted positions permits operation of the machine.

With these and incidental objects in view, the invention consists of certain novel features of construction and combinations of parts, the essential elements of which are set forth in appended claims and a preferred form or embodiment of which is hereafter described with reference to the drawings which accompany and form a part of this specification.

In the drawings:

Fig. 1 is a side view, partly broken away, of a manipulative state-controlling means and the mechanism operated thereby to lock the machine against operation when the controlling means is adjusted to certain of its positions.

Fig. 2 is a fragmentary view in front elevation of the key-operated lock to control the effectiveness of the machine release lock.

Fig. 3 is a detail side view of the machine releasing mechanism.

Fig. 4 is a fragmentary view in side elevation of the means for rocking the releasing shaft to free the machine for operation.

General description

A cash register of the type disclosed in Letters Patent of the United States, No. 1,242,170, issued to F. L. Fuller, October 9, 1917, and No. 1,619,796, issued to B. M. Shipley, March 1, 1927, has been selected to illustrate one embodiment of this invention.

The type of machine above referred to is usually provided with a plurality of totalizers and the necessary mechanism to accumulate amounts thereon under the control of manipulative amount and totalizer-selecting keys. The main operating mechanism of such machine is under the control of the usual release shaft which, in turn, is under the control of certain totalizer-selecting keys, and particularly a machine release bar. The manipulative state-controlling lever usually controls the machine in totaling and sub-totalizing operations, and selects the particular group of totalizers out of a plurality of such groups, from which a particular totalizer is to be selected by the totalizer-selecting keys on total and sub-total taking operations.

The state-controlling lever in the machine of the above mentioned patents usually has an adding position, three positions in one direction from the "adding" position known as "sub-total" positions, one for each group of totalizers; and three positions in the opposite direction from the "adding" position, known as the "total" positions, one for each group of totalizers. When the machine was operated with the state-controlling lever in the "adding" position, amounts were added onto any of the selected totalizers. When the machine was operated with the state-controlling lever adjusted to one of its "sub-total" positions, a sub-total was taken from the key-selected totalizer of the particular group selected by the position of the state-controlling lever. The "total" positions

of the state-controlling lever controlled the machine to print the total of, and reset the selected totalizer to zero.

In order to prevent operation of such machines with the manipulative state-controlling lever in certain of its positions, other than the "add" position, bolts have been provided to prevent movement of the lever into those positions.

With such construction, when the proprietor desired to prevent operation of the machine with the state-controlling lever in its first position out of the "add" position, he merely turned a removable key in a lock to project a bolt or plate across the path which the state-controlling lever would have to take to reach this position, the bolt effectually preventing movement of the state-controlling lever into the particular position. However, locking the state-controlling lever out of the first position, effectively locked it out of the second and third positions also. This condition is often undesirable, and is admirably overcome by applicant's device, which permits free movement of the lever into any of its several positions, and functions to prevent the operation of the machine when the lever occupies certain of its positions.

Reference may be had to the above-mentioned patents for a more thorough disclosure of the functions and operation of the machine in connection with which the present invention is illustrated.

Machine lock and release

Included in the machine is the usual release shaft 30 (Figs. 1, 3 and 4) journaled in the side frames 31 and 32 of the machine. These side frames correspond to the main machine frame of the machine, as disclosed in the above patents.

When it is desired to release the machine for operation, it is necessary to rock the release shaft 30 slightly clockwise in order to release the main driving mechanism (not shown herein). A spring 33 (Fig. 4) compressed between the bottom of a slot 34 in a restoring link 35 and a spring retainer 36 on a stud 37 in an arm 38 fast on the release shaft 30, constantly tends to rock the arm 38 and the release shaft 30 in clockwise direction, but a locking detent 39 (Fig. 3) journaled on a shaft 40 supported between the side frames 31 and 32, normally restrains the release shaft 30 against the action of the spring 33 by obstructing the advance of a stud 41 carried by a locking arm 42, also fast on the release shaft 30.

The upper end wall of the slot 34 (Fig. 4) in the link 35 lies above and apart from the stud 37 of the arm 38 carried by the release shaft 30. A rocking arm 73 pivoted at 74 to the frame of the machine, carries a roll 76 projecting into a cam race 77 formed in the side of a gear 78 journaled at 79, rotation of which gear rocks the arm. A pin 72 on the arm projects into an opening 75 formed in the restoring link, the pin normally lying in contact with the upper end wall of the opening 75 to support the link 35 in the position described, and shown in Fig. 4.

To release the machine for operation, the operator depresses a release bar 48 (Fig. 3) to move the locking detent 39 out of the path of the stud 41, whereupon spring 33 is free to expand and rock the shaft 30 in clockwise direction to enable the machine to operate. The release bar 48 is removably mounted on a slide 49 supported by a pair of screw studs 50 projecting

from the side frame 32, the slide carrying a stud 51 projecting through an open slot in an arm 52 of a lever 53 pivoted on a stud 54 in the side frame 32. The release bar 48, when depressed, shifts the slide 49 to rock the lever 53 counter-clockwise against the tension of a restoring spring 47. A stud 55 carried by the other arm 56 of the lever 53 projects through an open slot in an arm 57 forming one end of a yoke 58 journaled on the shaft 40. The yoke 58 connects the arm 57 with an arm 59, the hooked end of which overlies a stud 65 carried by an arm 66 forming part of a second yoke 68, the remaining arm 67 of which is forked to embrace a stud 69 projecting from the locking detent 39 journaled on the shaft 40 and yieldingly held by a spring 43 in effective position in the path of the stud 41 on locking arm 42 fast on the release shaft 30. The intermediate lever 53, when rocked counter-clockwise, rocks the yoke 58 clockwise to cause the hooked arm 59, to take over the stud 65 on the arm 66, to rock this arm and the yoke 68 also in a clockwise direction, whereupon the arm 67 of the yoke 68, embracing the stud 69 projecting from the locking detent 39, rocks the locking detent 39 counter-clockwise to raise the free end thereof out of the path of the stud 41. This frees the release shaft 30 to the action of the spring 33 (Fig. 4) which rocks the shaft 30 clockwise, as explained above, to release the machine for operation. The clockwise movement of shaft 30 is limited by a tail 70 on arm 38 (Fig. 4) striking a stud 71 projecting from the side frame 32.

Near the end of an operation of the machine, the release shaft 30 rocks counter-clockwise past its normal position to perform various functions, among which are that of releasing the depressed amount and transaction keys (not shown), and of restoring or permitting the restoration of the locking detent 39 to its normal obstructing position. Mechanism for rocking the release shaft 30 counter-clockwise and then clockwise to the position in which it appears in Fig. 3, will now be described.

When, upon depression of the release bar 48, the spring 33 rocks the shaft 30 clockwise, the stud 37 (Fig. 4) on the arm 38 of the release shaft assumes a position at or near the upper end of the slot 34 in the restoring link 35. Near the end of the operation of the machine, the gear 78 forming part of the drive mechanism of the machine has rotated sufficiently to bring a cam rise 80 in the cam groove 77 formed therein, to bear on the roll 76 of the restoring arm 73. This cam rise 80 imparts a short quick oscillation to the restoring arm 73 and, by reason of the location of the stud 72 of the restoring arm 73 in an offset notch of the opening 75 formed in the restoring link 35, the link is drawn downwardly past its normal position to perform the functions above stated, and then is moved upwardly to its normal position. As the link is drawn downwardly the upper end of the slot 34 in the link draws the stud 37 therewith to rock the release shaft 30 and its locking arm 42 counter-clockwise past their normal positions, whereupon the spring 43 returns the locking detent 39 to effective position in front of the stud 41 on the locking arm 42 to lock the release shaft and the parts controlled thereby against clockwise travel past the detent.

The gear 78 makes one-half of a rotation in counter-clockwise direction at each adding operation of the machine, and one complete rota-

tion in counter-clockwise direction at each totalizing operation of the machine. Any suitable means may be employed to effect these variable rotations.

5 On its reciprocatory movement, the restoring link 35 is guided by a stud 85 carried near one end of a pitman 86 adapted to slide over the stud 79 and supported at its left-hand end by an arm 87 of a lever 88 pivotally supported on the stud 74. The restoring link 35 on the upward movement imparted thereto by the cam 80, compresses spring 33 preparatory to releasing the machine for its next succeeding operation, the spring 33 operating through arm 38, and release shaft 30 to press the stud 41 of the locking arm 42 against the locking detent 39.

State-control of machine

Before the machine is released for operation 20 in the manner above described, various elements therein are adjusted to set the mechanism to perform the desired operation, such as adding, sub-totalizing or totalizing. This control is principally effected in the present instance, by the 25 well known control lever 91 (Fig. 1) which is adjustable to a plurality of positions corresponding to the particular kinds of operations which it is desired to effect. It will be noted from Fig. 1 that the control lever 91 has one "add" position, three "sub-total" positions, and three 30 "total" positions.

When the control lever 91 is in its "add" position, the various elements of the machine are adjusted to add the amounts set up on the 35 amount keys (not shown) into one or more of a plurality of selective totalizers (also not shown) with which the machine is provided.

When the control lever 91 is in any of its "sub-total" positions, the various elements are 40 adjusted to take the total from the particular totalizer selected, print and indicate the total, and then replace said total on the totalizer from which it was taken.

When the lever 91 occupies any one of its three 45 "total" positions, it controls the machine to take the total from a selected totalizer, print and indicate said total, and leave the totalizer from which the total was taken, standing at zero.

The machine chosen to illustrate the present 50 invention is provided with three groups or lines of totalizers, as is fully set forth in the above patents.

The three "sub-total" positions and three 55 "total" positions of the lever 91 are designated as follows: The first position from the "add" position in either direction is indicated by "A", the second as "B", and the third as "C". Movement of the control lever 91 to the first position in either direction from the "add" position selects the same group of totalizers, namely, the "A" group, for engagement with totalizer actuators (not shown). Likewise, movement of the lever 91 to either of the "B" positions, or either 60 of the "C" positions, determines that the "B" group or "C" group of totalizers is to be engaged with the actuators.

The foregoing mechanisms are old and only 65 form a part of this invention now to be set forth insofar as they coact therewith to accomplish the desired results.

Proprietor's automatic machine lock

During an adding operation of the machine, the amount set up on the amount keys (not 70 shown) may be accumulated upon one totalizer

selected in each of the three groups of totalizers (not shown). However, when a total is taken from a totalizer, but one totalizer may be engaged with the actuators at one time. It frequently happens that the proprietor prefers to 80 keep the totals of one or more groups of totalizers secret, that is, to prevent unauthorized persons from obtaining knowledge of the totals of the amount of business transacted, or to prevent them from restoring the totalizers of certain groups to zero. Obviously, this may be, and in the past has been, accomplished by blocking the adjustment of the control lever 91 out of the position which it must occupy to select the particular totalizer containing the total that 85 it is desired to keep secret. While this method is effective, it is subject to the following disadvantage, among others. Assuming that positions "A" control the selection of the secret totalizer, if these positions are rendered inaccessible to 90 the control lever, the positions "B" and "C" are also made inaccessible, as the lever has to pass position "A" in either direction before reaching positions "B" and "C". Likewise if the proprietor desires to render positions "B" inaccessible to the control lever 91, the "A" positions will be accessible, but it will be impossible for the operator to move the lever to either of the "C" positions, as well.

Obviously, this would materially reduce the 135 uses to which the machine could be put.

The present invention eliminates the above objectionable condition by rendering accessible to the control lever all positions to which it may be adjusted, at the same time effectively locking 110 the machine against operation when the control lever occupies certain of said positions. For illustrative purposes, the invention has been so arranged as to render the machine inoperative when the state-controlling lever 91 is adjusted 115 to either of its "A" positions. The effectiveness of this machine lock is contingent upon a tumbler or other suitable lock, the key to which may be removed and retained in possession of the proprietor or his duly authorized agent. 120

The machine lock itself is simple in structure, novel in arrangement, and adds no burden to the operation of the machine.

The control lever 91 projects from the usual control disk 92, a fragment of which appears 125 in Fig. 1, journaled on a stud 93, projecting from the side frame 32. The control lever 91 projects through and is rockable along a slot formed longitudinally in a frame 94 supported on cross rods 95 and 96, extending between the side 130 frames 31 and 32. The side wall of the slot in the frame 94 is provided with a plurality of spaced index notches, one corresponding to each of the several positions to which the control lever 91 is adapted to be adjusted. The 135 lever 91 is shown in Fig. 1 as occupying the first or "A" position below the "add" position, namely, the "A to al" position.

A thrust bar 98 is pivotally mounted near its opposite ends on the links 99 and 100, respectively, carries a projection or roll 97 entered in a cam slot 101 formed in the state-controlling disk 92. The supporting link 99 is pivoted on a rod 102, extending between the side frames 31 and 32, and the supporting link 100 is pivoted on a 146 stud 103 eccentrically mounted on an actuating disk 104 fast on the inner end of the rotatable barrel 105 of a lock 106 projecting inwardly from the side frame 32.

The configuration of slot 101 in the present 150

illustration is such that movement of the control lever 91, and consequently of disk 92, an equal distance in either direction from its "add" position rocks the supporting links 99 and 100 in counter-clockwise direction and shifts the thrust bar 98 towards the left in the direction of its length for a distance determined by the distance the control lever is moved from its "add" position. Stated in another way, if the control disk 92 is rocked clockwise one step which is sufficient to shift it from its "add" position to its "sub-total A" position, the cam slot 101 co-operating with the roller 97 on the thrust bar 98 rocks the latter towards the left one step. Adjustment of the control lever 91 and control disk 92 counter-clockwise from its "add" position to its "total A" position, (shown in Fig. 1), shifts the thrust bar 98 again towards the left in the direction of its length the same distance or single step through which the thrust bar is shifted when the lever 91 and disk 92 were moved to the "A sub-total" position.

The conformation of the slot 101 is such that the control lever 91 shifts the thrust bar 98 a variable distance, that is, when the control lever 91 is rocked two steps to one its "B" positions, it moves the thrust bar 98 farther towards the left than when the control lever is shifted to one of its "A" positions. Likewise, movement of the control lever 91 to either of its "C" positions imparts a still greater travel to the thrust bar 98.

A cam face 110 is formed on the thrust bar 98 to cooperate with a stud or projection 111 extending from a link 112 pivoted at one end to a link 113 swinging on the frame 94, and at its opposite end to an arm 114 of a bell crank 115 journaled on the shaft 40. The other arm 116 of bell crank 115 forms a stop arm or arresting member adapted to cooperate with a stud 117 on an arm 118 fast on the release shaft 30, and under certain conditions obstruct the clockwise movement of the arm 118 and release shaft 30. A spring 119 tends to draw the link 112 to the left (in Fig. 1) to rock the bell crank 115 clockwise and displace the stop arm or arresting member 116 from the path of the stud 117. So long as the control lever 91 remains in its "total A" position, as shown in Fig. 1, however, the cam face 110 on the thrust bar 98, by contact with the stud 111, will maintain the link 112 and bell crank 115 in the positions shown, to prevent clockwise movement of the release shaft 30, and hence prevent operation of the machine. The same condition obtains when the control lever 91 occupies its "sub-total A" position.

The control lever 91, when shifted from either of its "A" positions to its "add" position, rocks the supporting links 99 and 100 clockwise and draws the thrust bar 98 towards the right to withdraw the cam face 110 from its restraining relation with the stud 111, whereupon spring 119 acts to draw the link 112 to the left to rock the bell crank 115 clockwise, and lower the stop arm 116 out of the path of the stud 117. The machine may now be released for operation by depression of the release bar 48, as described above.

If the control lever 91 is moved to its "sub-total A" position, the same locking condition prevails, inasmuch as the cam face 110 is brought to the same position in which it is shown in Fig. 1. When, however, the lever 91 is shifted to either of its "B" or "C" positions, the conformation of the slot 101 will operate to rock the supporting links 99 and 100 farther counter-clockwise, thereby shifting the thrust bar 98

further towards the left and withdrawing the cam face 110 from its restraining or effective position. This, of course, permits the spring 119 to render the arresting means 116, ineffective, as explained above.

As heretofore stated, the proprietor or his agent may wish to read or reset the totalizer or totalizers of line or group "A" containing the secret totals, at certain intervals, for instance, at the end of the day's business, or at the end of each week. To do so, he inserts a key 120 (Fig. 2) into the lock 106 and rotates the barrel 105 thereof counter-clockwise, as viewed in Fig. 1, thus rotating the actuating disk 104 to which the lower end of the supporting link 100 is pivoted. This rotation, through the eccentric mounting of the link 100 on the actuating disk, lowers the link and the thrust bar 98 to withdraw the cam face 110 from its restraining position, whereupon spring 119 rocks the stop arm 116 to free the release shaft 30 to the control of the locking detent 39 (Fig. 3), which, when displaced from the path of stud 41 on the locking arm 42, by depression of the release bar 48, frees the machine for operation. After having read or reset the particular totalizer or totalizers desired, the proprietor, by means of his key 120, returns the barrel 105 of the lock 106 and the actuating disk 104 to the positions shown in Fig. 1, thereby raising the link 100 and the thrust bar 98 to restore the stop arm 116 to its effective blocking position.

It is evident that by variously forming the cam slot 101 or the cam face 110 or both, the effectiveness of the stop arm 116 may be varied to enable the controlling lever to prevent operation of the machine when it is in any one or more of its pairs of corresponding positions above and below the "add" position.

The spring 33 (Fig. 4) which tends to turn the release shaft 30 in clockwise direction is stronger than the spring 119 (Fig. 1) which operates through the link 112 to disable the stop arm or arresting means 116. Therefore, to prevent the force of the release shaft spring 33, exerted through the shaft, from retarding or entirely preventing the spring 119 from disabling the arresting member 116, the detent 39 is slightly longer than the stop arm 116, to sustain the pressure exerted by the spring 33.

Also, it is evident that in the example shown, the stop arm or arresting member 116 remains where adjusted by its spring 119 and is not restored to effective position relatively to the release shaft 30 except by the adjustment of the control lever to such position that the thrust bar 98 effectively operates the arresting member.

Hence it is desirable to use this type of machine lock in connection with the usual form of machine lock typified by the locking detent 39, to insure the retention of the release shaft in locked position at the end of every operation of the machine.

It may be desirable to preserve a record of the number of times the lock 106 is actuated, so that the proprietor may have a check on the number of times the totalizers are read or reset. This information is useful in that, by noting the number of operations of the lock, the proprietor may know if the lock has been operated by a person unauthorized to read or reset the totalizer. For this purpose a step-by-step counter of the Veede type, or any other suitable type, is attached to the machine as indicated at 125 (Fig. 1). The operating crank 126 for this

- counter is pivotally connected to a pitman 127 forked at its inner end to slidably embrace a circumferentially grooved collar 128 surrounding the barrel 105 of the lock 106. A stud 129 on the pitman 127 projects into the path of a shoulder on the periphery of the actuating disk 104. When the barrel 105 of the lock 106 turns counter-clockwise to render the stop arm 116 ineffective, the actuating disk 104 operating on stud 129, shifts the pitman 127 towards the left, rocking the crank 126 clockwise to advance the counter 125 one step. When the key 120 is turned clockwise to return the barrel 105 and disk 104 in clockwise direction to render the stop arm 116 effective, a spring 130 restores the pitman 127 to the position in which it is shown in Fig. 1, thereby rocking the crank 126 counter-clockwise preparatory to another driving movement thereof.
- 20 While the form of mechanism herein shown and described is admirably adapted to fulfill the objects primarily stated, it is to be understood that it is not intended to confine the invention to the one form or embodiment herein disclosed, for it is susceptible of embodiment in various forms all coming within the scope of the claims which follow.
- What is claimed as new, is:
1. In a machine of the class described; the combination with a release shaft; means to rock said release shaft to release the machine for operation; means to obstruct the releasing movement of the shaft; and means to displace such obstructing means; of a second means independent of the first-named obstructing means, to lock the machine against operation; means to disable the last-named locking means; and a plurality of manipulative means to control the effectiveness of the second-named disabling means.
  2. In a machine of the class described; the combination with a release shaft; means to rock said release shaft; a means to obstruct the rocking of the release shaft in one direction; and means to displace the obstructing means; of a second means to obstruct the rocking movement of the release shaft in one direction; a spring to disable the second-named obstructing means; and a plurality of manipulative means to control the action of said spring.
  3. In a machine of the class described; the combination with a release shaft; and means to give said shaft a releasing movement of movable means to obstruct the releasing movement of the shaft; a spring to displace such obstructing means; a thrust member to set the obstructing means to effective position against the tension of the spring; and a plurality of means to disable the thrust member to enable the spring to become effective.
  4. In a normally locked machine of the class described, the combination with a machine release shaft; and means to turn the shaft in its releasing direction; of a stop arm to obstruct the movement of the shaft in such direction; a link connected to the stop arm, a spring to actuate the link to disable the stop arm; and means to restrain the link against operation by the spring to prevent disabling the stop arm.
  5. In a machine of the class described, the combination with a release shaft; and means to turn the shaft in its releasing direction; of a stop arm to obstruct the movement of the release shaft in such direction; a link connected to the stop arm; a spring attached to said link to disable the stop arm; means operable upon the link to retain the stop arm in effective position; and means to withdraw the retaining means.
  6. In a machine of the class described; the combination with a release shaft; and means to turn the shaft in its releasing direction; of means to prevent movement of the shaft in such direction, including a shiftable arresting member, and a link to control the position of the arresting member; a spring to render the arresting member ineffective; a thrust bar operable upon the link to retain the stop arm effective; and a plurality of separately operable means to withdraw the thrust bar.
  7. In a normally locked machine of the class described; the combination with a machine release shaft; of means to prevent releasing movement of the shaft, including an arresting member shiftable to effective and ineffective positions; an adjustable device movable into a plurality of positions; means controlled by the adjustable device, when moved into any one of its positions, to determine the effectiveness of the arresting member; and manipulative means to render the arresting member ineffective when the adjustable device is in any one of the positions in which the device renders the arresting member effective.
  8. In a normally locked machine of the class described; the combination with a machine release shaft; of means to prevent releasing movement of the shaft, including an arresting member shiftable into and out of effective position; an adjustable device movable into a plurality of positions; means controlled by the adjustable device, when moved into any one of its positions, to determine the effectiveness of the arresting means; and means operable upon the means controlled by the adjustable device to render the arresting means ineffective when the adjustable device is in any one of the positions in which the device renders the arresting member effective.
  9. In a normally locked machine of the class described, the combination with a machine release shaft; and means to give the shaft a releasing movement; of a shiftable locking means to prevent the releasing movement of the shaft; adjustable means to control the effectiveness of the shiftable locking means; and means to render the locking means ineffective when the adjustable means is set to any one of a plurality of positions to render the locking means operative.
  10. In a machine of the class described, the combination with an adjustable control device; of an arresting member; a pivotally supported thrust bar differentially shiftable by the control device to determine the effectiveness of the arresting member; and a manually operated lock to control the effectiveness of the thrust bar.
  11. In a machine of the class described, the combination with an adjustable control device having a cam; of an arresting member; a pivotally supported thrust bar shiftable by the cam of the control device to determine the effectiveness of the arresting member; a manually operable lock member; and a link to connect the lock member and the thrust bar to enable the lock member to determine the effectiveness of the thrust member.
  12. In a machine of the class described, the combination with an arresting member shiftable into and out of effective position; and an adjust-

- able control device; of a pivotally supported thrust member controlled by the adjustable device and operable upon the arresting member to determine the effectiveness thereof; a rotatable lock member; and a link eccentrically pivoted to the lock member, and connected with the thrust member to disable the latter regardless of the position of the adjustable device.
13. In a machine of the class described, the combination with an arresting member shiftable into and out of effective position; and an adjustable control device; of means tending to shift the arresting member to one of its positions; a thrust member pivotally supported for differential movement in one direction and for constant movement at substantial right angles thereto and operable by the control device to determine the effectiveness of the arresting member; and means operable upon the thrust member to determine its effectiveness regardless of the control device.
14. In a machine of the class described; the combination with a release shaft; means to rock said release shaft to release the machine for operation; means to obstruct the releasing movement of the shaft; means to displace such obstructing means; of a second means adapted to obstruct the releasing movement of the shaft; means to disable the second-named obstructing means; a device to prevent operation of the disabling means; and a differentially adjustable member to render said device ineffective when the differentially adjustable member is in certain of its fully adjusted positions only.
15. In a machine of the class described; the combination with a release shaft; means to rock said release shaft to release the machine for operation; means to obstruct the releasing movement of the shaft; means to displace such obstructing means; of a second means adapted to obstruct the releasing movement of the shaft; means to displace the second-named obstructing means; a member pivotally supported for differential movement in one direction and for constant movement in another direction to determine the effectiveness of said disabling means; and a plurality of manipulative devices to operate said member.
16. In a machine of the class described; the combination with a release shaft; means to rock said release shaft to release the machine for operation; means to obstruct the releasing movement of the shaft; means to displace such obstructing means; of a second means adapted to obstruct the releasing movement of the shaft; means to displace the second-named obstructing means; a member pivotally supported for differential movement in one direction and for constant movement in another direction to determine the effectiveness of said disabling means; differentially adjustable means to give said member its differential movement; and a constantly movable means to give said member its constant movement.
17. In a machine of the class described; the combination with a release shaft; and means to rock the shaft to release the machine; of means to obstruct the releasing movement of the shaft; a member connected to the obstructing means; resilient means to actuate the member to disable the obstructing means; an adjustable device adapted when moved to a certain controlling position to restrain the member against operation by the resilient means to prevent the disabling of the obstructing means.
18. In a machine of the class described; the combination with a release shaft; and means to rock the shaft to release the machine; of means to obstruct the releasing movement of the shaft; a member connected to the obstructing means; resilient means to actuate the member to disable the obstructing means; an adjustable device adapted when moved to a certain controlling position to restrain the member against operation by the resilient means to prevent the disabling of the obstructing means; and a differentially adjustable element to control said device.
19. In a machine of the class described; the combination with a release shaft; and means to rock the shaft to release the machine; of means to obstruct the releasing movement of the shaft; a member connected to the obstructing means; resilient means to actuate the member to disable the obstructing means; an adjustable device adapted when moved to a certain position to restrain the member against operation by the resilient means to prevent the disabling of the obstructing means; a differentially adjustable element to control said device; and a manually operable member connected to said device to control the effectiveness thereof.
20. In a machine of the class described; the combination of a release shaft; arresting means therefor; an adjustable control device having camming means; a thrust bar supported by a pair of links, the pivot of the bar of one link co-operating with the camming means whereby the latter may effect movement of the thrust bar to determine the effectiveness of the arresting means; and means cooperating with and connected to the other supporting link for the thrust bar to determine the effectiveness of the thrust bar.
21. In a normally locked machine of the class described; the combination of a control device having a normal position and a plurality of positions of adjustment; a machine release shaft; arresting means therefor; and means controllable by the control device whereby the arresting means is ineffective when the control device is in its normal position, and effective when the control device is in any one of a certain plurality of its controlling positions of adjustment.
22. In a normally locked machine of the class described; the combination of a control device having a normal position and a plurality of positions of adjustment; a machine release shaft; arresting means therefor; and means controllable by the control device whereby the arresting means is ineffective when the control device is in its normal position, and effective when the control device is in any one of a certain plurality of its positions of adjustment; and means to determine the effectiveness of the controllable means regardless of the position of the control device.
23. In a machine of the class described; the combination of a release shaft; arresting means therefor; an adjustable control device; a member cooperating with the arresting means; a pair of links supporting said member, both of said links being rockable by the adjustable control device to operate said member to determine the effectiveness of the arresting means; and means to shift one of the links substantially in the direction of its length to rock said member to remove the control thereof over the arresting means.

WILHELM KROPFF.
